STORAGE CARRYING CASE FOR MAGNETIC TAPE CARTRIDGES

Albert A. Di Ioia, 401 County Line Road,
Huntington Valley, Pa. 19006

Filed Feb. 3, 1970, Ser. No. 21,242

Term of patent 14 years

Int. Cl. D3—99

U.S. Cl. D87—1

FIG. 1

FIG. 2

FIG. 3

FIG. 4

FIG. 5

FIG. 1 is a front perspective view of a storage carrying case for magnetic tape cartridges showing my new design;

FIG. 2 is a rear perspective view thereof;

FIG. 3 is a right side view thereof;

FIG. 4 is a bottom view thereof;

FIG. 5 is a front perspective view thereof in open condition.

I claim:

The ornamental design for a storage carrying case for magnetic tape cartridges, as shown.
